CLAIM

The ornamental design for a package for data medium, as shown and described.

DESCRIPTION

FIG. 1 is a front view of a package for data medium; according to our new design;
FIG. 2 is a first side view thereof;
FIG. 3 is a rear view thereof;
FIG. 4 is a second side view thereof at a 90° degree angle compared to FIG. 2; and,
FIG. 5 is a front perspective view thereof.
